DESIGN FOR A SKI SANDAL

George William Lothrop, Wayne, Mich.

Application April 3, 1948, Serial No. 145,512

Term of patent 7 years

(Cl. D7—7)

To all whom it may concern:

Be it known that I, George William Lothrop, a citizen of the United States, residing in the city of Wayne, county of Wayne, and State of Michigan, have invented a new, original, and ornamental Design for a Ski Sandal, of which the following is a specification, reference being had to the accompanying drawing, forming part thereof.

Fig. 1 is a top plan view; and

Fig. 2 is a side elevational view of a ski sandal, showing my new design.

I claim:

The ornamental design for a ski sandal, as shown.

GEORGE WILLIAM LOTHROP.
